UNITED STATES PATENT OFFICE.

JOHN RICARDS LONG SANTOS, OF BALTIMORE, MARYLAND, ASSIGNOR TO THE BARTLETT HAYWARD COMPANY, OF BALTIMORE, MARYLAND, A CORPORATION OF MARYLAND.

GAS HOLDER.

Application filed July 10, 1928. Serial No. 291,615.

This invention relates to metallic structures and particularly to gas holders of the so-called waterless type in which a diaphragm or piston moves upward bodily in a structure 5 of generally polygonal form. Such structures as ordinarily built include columns at the angular junction of each pair of side walls and as heretofore constructed these columns have projected slightly within the line of the walls 10 producing interruptions in the general contour of the interior of the gas holder which greatly complicate the sealing or packing of the joint between the piston and the walls of the gas holder.

15 The purpose of the present invention is to produce a structure adapted to commercial use and avoiding the above defect.

Generally stated, use is made of a column having a web or webs bounded by marginal flanges. For example an I-beam is the simplest form and is preferred but other girder and column sections having similar characteristics are well known and are not excluded from the scope of the present invention.

20 25 With these columns are used wall units of channel section. These might be conventional channels but in the preferred form of the device assume a special configuration which will be explained. These wall units are assembled horizontally with their flanges abutting and riveted together and with the ends of their webs abutting the inner flanges of the columns. In this way a flush joint is produced between the webs of the wall sections 30 and the inner flanges of the columns and these flush joints are welded producing a gas-tight structure with a virtually smooth internal wall.

In order to brace each of the wall sections 40 to the column section a box-like connector unit is used comprising a plate having marginal flanges on three sides. This connector is dimensioned to fill the channel of the wall section at the end thereof and to lap one of the 45 channel faces of the inner flange of the column and abut against the web. The parts so far described are connected by rivets which pass exclusively through the flanges of the wall units and the connectors and through the 50 web portion of the column. There are thus no rivets extending through to the interior face of the wall of the gas holder.

The structure is further braced by connecting the extremities of the flanges of the wall

sections with the outer flanges of the column 55 and with each other. This is conveniently done by riveting straps to these parts though it might be accomplished in other equivalent ways.

In the accompanying drawing the preferred construction is illustrated by showing one column and the abutting portion of two adjacent vertical series of wall sections. It will be understood, however, that the complete holder structure is made up of a plurality of spaced columns with intervening wall sections. Ordinarily the spacing of the columns is uniform but this is not necessarily the case.

In the drawing,

Figure 1 is a horizontal section; and

Figure 2 is a fragmentary perspective view.

The column consists of a heavy I-section 6 made up as usual of a web 7 and tapered flanges 8. Each wall section is of general 75 channel form and comprises a web portion 9 which, when assembled, forms the major portion of the wall of the gas holder; a relatively short lower flange 11; a wide upper flange 12; and a combined stiffener and drip 80 flange 13.

The wall sections are bent up of plate and are not as here illustrated rolled sections.

The column 6 is a rolled section.

The wall sections are assembled with the 85 flange 11 of one section resting on the flange 12 of the next lower and the webs 9 of the sections flush with each other and presented toward the interior of the tank. The ends of the webs 9 of the wall sections are welded as 90 indicated at 14 to the extremities of the tapered flanges 8. The joint so formed is reinforced by pressed steel stiffener plates, indicated generally by the numeral 15, applied to the main plate portion. These stiffener 95 plates are generally rectangular in shape and are formed with a continuous flange 16 extending around three sides of the plate.

The plate 15 lies against the web 9 with the flange 16 at the top and bottom abutting the 100 flanges 11 and 12. The web 8 is so formed relatively to the thickness of the wall unit 9 and the angle between such wall units that each plate 15 lies flush against the channel side of the web 8.

Furthermore, that portion of the flange 16 which abuts the web 7 of the column is set at an appropriate angle so as to seat over

its entire face against the web. The wall sections are connected by rivets 17, certain of which pass only through the flanges 11 and 12 and others of which pass through these flanges and also through the flanges 16 of two adjacent connector plates 15. There are also rivets 18 which pass through the flanges 16 of two connector plates 15 and also through the intervening web 7 of the column.

10 In order to tie the structure together straps 19 are riveted at 21 to the outside flange of the column 6 and at 22 to the stiffener flange 13.

15 The flanges 12 are dimensioned to accommodate the tie 19 as is clearly shown in Figure 1.

20 Other means for connecting the flange 13 with the outer flanges 8 of the column might be substituted, the primary purpose being to secure angular bracing.

25 The structure above described presents a smooth surface on the interior of the gas holder being free of rivet heads and all other projections. While it is preferred to weld the joint 14 any procedure which would seal this joint satisfactorily might be substituted for the weld. The weld, however, contributes to the strength of the structure and is preferred.

30 Obviously various changes might be made in the details of the structure and the embodiment described is to be considered as illustrative rather than limiting. For example, while it is preferred to use wherever possible an I-beam for the column 6 so dimensioned that the channel side of the flange 8 is in plane with the inner face of the web of the wall section conditions may be encountered where this is impracticable. Obviously it is not 35 strictly essential because the pressed steel connector plates 15 can be so formed with offsets as to fit any desired flanged contour. Nor is it strictly necessary that it fit the contour of the flange 8. In other words, although there has been shown a construction in which the channel face of the flange 8 is in plane with the web of the wall section 9 it is not regarded as being strictly essential to the invention.

40 50 What is claimed is:

1. In a gas holder structure, the combination of a column having a web with a marginal flange; channel-shaped wall sections assembled in horizontal relation with their flanges abutting and with the ends of the webs abutting the flange of the column and welded thereto; and bracing means for connecting the flanges of the wall sections with the web of the column.

60 65 2. In a gas holder structure, the combination of a column having a web and marginal flanges; a plurality of channel-shaped wall sections assembled in horizontal relation with their flanges abutting and the ends of their webs abutting one flange of the column and

welded thereto; and bracing means connecting flanges of the wall sections with the web and with the other flange of the column.

70 3. In a gas holder structure, the combination of a column having a web and marginal flanges; a plurality of channel-shaped wall sections assembled in horizontal relation with their flanges abutting and the ends of their webs abutting one flange of the column and welded thereto; and bracing means connecting flanges of the wall sections with the other flange of the column.

75 4. In a gas holder structure, the combination of a column having a web and a marginal flange; channel-shaped wall sections assembled with their flanges abutting and the ends of their webs abutting the flange of the column and welded thereto; connector plates each flanged on three edges, each filling the channel at the ends of the wall sections and lapping the inner face of a flange of the column and abutting the web of the column; and rivets passing through the flanges of the wall sections and connector plates and through a flange of the connector plates and the web of the column.

80 5. In a gas holder structure, the combination of a column having a web with marginal flanges; channel-shaped wall sections assembled with their flanges abutting and the ends of their webs abutting the inner flange of the column and welded flush thereto; connector plates having flanges on three edges, each connector plate filling the channel at the ends of the wall sections, lapping the channel face of the inner flange on the column and abutting the web of the column; rivets passing through the flanges of the wall sections and connector plates and through a flange of the connector plates and the web of the column; and means connecting the flanges of the wall sections with the outer flange of the column.

85 100 105 6. A gas holder structure comprising in combination, a column of I-section; substantially horizontally extending channel-section wall units assembled with their flanges abutting and directed outward and with their webs flush and welded flush to the inner flanges of the column; flanged braces engaging the webs and flanges of the wall sections and the web and inner flange of the column; and connectors serving to hold the above enumerated parts together and passing exclusively through the flanges of the wall sections and connectors and through the web of the column.

110 115 120 125 7. A gas holder structure comprising in combination, a column of I-section; substantially horizontally extending channel-section wall units assembled with their flanges abutting and directed outward and with their webs flush and welded flush to the inner flanges of the column; flanged braces engaging the webs and flanges of the wall sections

and the web and inner flange of the column; and means connecting flanges of the wall sections with the outer flanges of the columns.

8. A gas holder structure comprising in combination, a column of I-section; substantially horizontally extending channel-section wall units assembled with their flanges abutting and directed outward and with their webs flush and welded flush to the inner flanges of the column; flanged braces engaging the webs and flanges of the wall sections and the web and inner flange of the column; and stays connecting flanges of aligned wall sections with the outer flanges of the column and with each other.

9. In a gas holder structure, the combination of a column having a web and marginal flanges; a plurality of channel-shaped wall sections assembled in horizontal relation with their flanges abutting and the ends of their webs abutting one flange of the column and

forming a sealed joint therewith; and bracing means connecting flanges of the wall sections with the web and with the other flange of the column.

10. In a gas holder structure, the combination of a column having a web and a marginal flange; channel-shaped wall sections assembled with their flanges abutting and the ends of their webs abutting the flange of the column and forming a sealed joint therewith; connector plates each flanged on three edges, each filling the channel at the ends of the wall sections and lapping the inner face of a flange of the column and abutting the web of the column; and rivets passing through the flanges of the wall sections and connector plates and through a flange of the connector plates and the web of the column.

In testimony whereof I have signed my name to this specification.

JOHN RICARDS LONG SANTOS.
